SURGICAL APPARATUS

John G. H. Liebel and Edwin S. Flarsheim, Cincinnati, Ohio, assignors to The Liebel-Flarsheim Company, Cincinnati, Ohio, a corporation of Ohio

Application April 5, 1933, Serial No. 664,574

9 Claims. (Cl. 128—422)

This invention relates to electro-surgical instruments of the general type disclosed in Liebel Patent No. 1,863,118, and Bovie Patent No. 1,813,902. While the devices disclosed in these two enumerated patents are entirely suitable for the field of usage for which they were intended, still there is a substantial demand for a type of instrument of extreme simplicity from the point of view of the technique of operation, yet sacrificing nothing in the quality of its modalities, and which provides all of the different types of electrical current which have been found suitable for surgical or therapeutic purposes.

One of the types of current, which the instrument of this invention is adapted to provide, is a surgical or cutting current possessed of dehydrating properties found as a result of years of experience to be suitable for providing hemostasis under normal conditions in operations of the general type for which electro-surgery has been found to be particularly efficacious. At the present time, the removal of cancerous tissue, intracranial tumors, both malignant and benign, and the transurethral removal of prostatic tissue, bladder tumors, etc., are examples of surgical operations in which electrical cutting is frequently used.

The surgical apparatus of this invention likewise provides coagulating current adapted to stop the flow of blood when particularly vascular tissue is dissected or when blood vessels or small arteries are encountered.

A third type of current, not usually employed in surgical operations but which has been found very useful for general therapeutic purposes, is the so-called diathermic current, the purpose of which is to generate heat within the tissues themselves either as a result of the passage of the current or inductively. The surgical apparatus of this invention likewise provides such a type of current.

At the present time, the type of diathermy treatment most usually administered is that wherein electrodes are fastened directly to the patient. On this account the description and drawings disclose circuits adapted to provide a type of current suitable for this treatment. These circuits, however, may be altered to provide the type of current used in diathermy treatment in which the electrodes are insulated from the patient and the heating effect secured by placing the patient in the high frequency electrostatic field.

The invention herein disclosed may be looked at from either one of two rather different points

of view. It can be looked at from the point of view of the electrical engineer or from the point of view of the surgeon. By and large the invention may be said to reside in selecting of instrumentalities from the electrical art and arranging them to solve the problems of the wholly unrelated surgical art.

In the accompanying drawings, Sheet 1 discloses the invention from the point of view of the surgeon; that is, discloses the adjustments and other elements with which the surgeon deals in performing the operation. Sheet 2, on the other hand, discloses the combination of electrical elements which provide the surgeon with the operative resources, found by these inventors, to be the most useful to the average surgeon in performing operations of the general type mentioned.

The major problem to be solved as a part of this invention was the determination of the requirements of the surgeon who is performing an operation by electro-surgery. It has been impossible for the surgeons to understand the electrical details of electro-surgical apparatus and on this account it has been difficult for the surgeons to make a multitude of adjustments or to operate a multitude of adjustments selectively and with good effect during a surgical operation. It has been the effort of the inventors in designing the present apparatus to do away with all adjustments which were not useful to the surgeon during an operation and to build into the machine the capacity to supply the surgeon with the types of current and the ranges of current determined by the inventors to be most useful to the surgeon on the basis of years of observation of thousands of actual operations.

Therefore, one object of the invention is to provide a surgical apparatus of the nature disclosed, wherein the mechanism accessible to the surgeon or to be used by the surgeon during the operation is extremely simple yet provides the surgeon with all of the modalities of current and the prompt selection of power requisite for performing surgical operations with the apparatus.

Another object of the invention is to provide an arrangement of electrical instrumentalities suitable for accomplishing the primary objective above specified.

Still another object of the invention is to provide an arrangement of the electrical instrumentalities of the simplest possible nature consistent with the complexity of the function, the arrangement characterized by the utilization of the greatest possible number of electrical instru-

mentalities as common elements in the different circuits providing the different modalities of current.

Other objects and further advantages will be more fully apparent from a description of the accompanying drawings.

In the accompanying drawings, Figure 1 is a perspective view of the control cabinet.

Figure 2 is a top plan view of the cabinet.

Figure 3 is a wiring diagram of the circuits and devices employed in the control cabinet.

Noting Figure 1, it will be observed that the surgical apparatus of this invention is provided with one set-up adjustment and three operating adjustment devices, the former being the spark gap setting 16, the latter being one current selector 11 and two power adjusters 12, 13.

The current selector may be moved to any one of four different positions, these being the off position, diathermy position, coagulation position, and scalpel or cutting position.

One of the power adjustments is for the scalpel or diathermy current and the other for the coagulation current. The point of this double power control is that in performing an operation, it is frequently necessary for the surgeon to shift rapidly back and forth between scalpel and coagulation positions. The scalpel current is usually used in one power range and the coagulation current in a different power range. If there were but one power control, then it would be necessary for the operator of the machine, during the operation, to readjust the power every time a shift was made from scalpel to coagulation or vice versa. With the two different power control devices, one may be set in the range appropriate for cutting and the other in the range appropriate for coagulation and generally the operator of the machine need only switch the selector back and forth between the scalpel and coagulation positions. In this way a great deal of time is saved during the course of an operation. In many of these operations, especially so in neuro-surgery and prostatic resection, time is an extremely important factor, often determining the success or failure of the operation.

Another feature of the invention is that the off position of the selector (see Figures 2 and 3) is disposed between the coagulation and diathermic positions so that there is little likelihood of the operator of the machine moving it to a diathermic position by accident during the progress of the operation.

Connected to the selector is a device (not shown) which tends to lock it or hold it in one of the four desired positions so that it cannot be brushed accidentally to an undesired position during the course of an operation. It is also to be noted that the handles 15 on the selector and the two power controls are detachable so that they may be sterilized before an operation, thereby permitting the surgeon himself to operate the device if necessary.

As disclosed there are four lead wires from the apparatus, one, namely 16, being adapted to be attached to the indifferent electrode, the other three, namely 17, being attached to active or operating electrodes. Attached to the apparatus cabinet is a removable electrode holder so that the electrodes and their holder can be sterilized before an operation and the surgeon remove any desired electrode from the holder without contaminating his fingers. Of course, it is to be recognized that different types of electrodes are used,

such as loops, wires, stylus electrodes, etc. Therefore, the surgeon's instrument, as a whole, is designed so that the surgeon can perform the entire operation single-handed if necessary, with no chance of infection and with a small number of adjustments readily understood and accessible, so that the surgeon's entire attention may be free from pre-occupation with the electrical problems and be concentrated entirely on the surgical problems.

The essential parts of this apparatus which is designed to produce cutting, coagulation, and diathermy current of satisfactory amounts of power and proper quality of each of these modalities, consist of a main transformer 18 which is in operation on cutting, coagulation and diathermy. An iron core inductance 19, which has two steps of inductance, is in the primary circuits of this transformer and is used for coagulation and diathermy respectively. The primary of the main transformer is designed for 110 to 120 volts or other supply line voltage available and the output is wound for 1400 volts. The output of the secondary of this transformer which is of the "leakage" type is connected to the spark gap 10 which is of special design allowing for compensated micro-metric adjustment and of the type disclosed in the Flarsheim Patent No. 1,696,157 granted December 18, 1928.

The spark gap is utilized on all three of the settings of scalpel, coagulation and diathermy. In addition there are three primary oscillating circuit condensers 22, 21, 20, which are used respectively on the three current modalities, and a specially designed resonator inductance 23 which is wound on two tubes, one inside of the other and which has various taps for primary and secondary, a different combination of which is used for each of the current modalities. In addition to the above, there is a potentiometer 24 which is used for controlling the output of the machine and also for selection of the two power controls, one of which controls the output for scalpel and diathermy and the other of which controls the output for coagulation. This particular arrangement is used to allow for immediate and instant change from scalpel to coagulation, which is absolutely essential to the convenient use of the apparatus for surgery.

Now, the change between the electrical selection of the above parts is accomplished through a specially designed five pole, four throw (three operating positions and an "off" position) selector switch.

In addition to selecting the proper primary and secondary electrical connections this selector switch is arranged so that on the scalpel and coagulation positions the foot switch 14 is operative, whereas on the diathermy setting the foot switch is not operative and the machine starts to function as soon as the selector switch is turned to the diathermy setting.

First we will consider the arrangement and connection of parts as used for the scalpel or cutting modality. The scalpel current must be of comparatively undamped characteristics approaching somewhat near a continuous wave current and to obtain this condition the connections made by the selector switch are as follows:

Current is fed directly from the input, indicated at 25, through a lead 26 to pole No. 2 through the scalpel contact 27, thence by way of lead 28 directly to the primary 30 of the main transformer. The circuit to the primary of the transformer is completed through lead 72, foot 75

switch 14, scalpel contact 68 of pole No. 1, then through lead 71 of the input.

The output of the main transformer at approximately 1400 volts is connected across the spark gap 10, from one side of which a lead 31 extends to pole No. 3 through the scalpel contact 32, thence by lead 33 through the .00175 micro-farad oscillating circuit condenser 22 to the 15 $\frac{1}{4}$ turn tap of the resonator inductance 23. From the start or zero turn of the resonator inductance 23, indicated at 34, the circuit leads back to the other side of the spark gap through a lead 35.

One end of the potentiometer coil 24 is connected to the zero turn tap of the resonator inductance coil through a lead 56. This combination of a very small capacity and a moderately large inductance is necessary to produce the slightly damped current in combination with a full and sustained output from the main transformer.

The output of the resonator inductance coil is taken from the zero tap indicated at 34 and from the 30% turn tap as at 36 from which it is led to the potentiometer through a lead 37 extending to the scalpel contact 38 of pole No. 4 and from pole No. 4 through a lead 39 to the potentiometer.

The selector switch also selects the proper power control for the output which is marked on the drawings "Scalpel and diathermy". This is done through pole No. 5 by way of power control slider 18, lead 40, scalpel contact 41, switch arm, and output lead 42 to the lead wires 17.

In the output lead 42, a meter 16 and a filter 17 are inserted. The purpose of the filter is to tune for the high frequency current and to block any low frequency current flow to the patient. It will also be noted that grounding condensers 78 and 79 are placed in leads 80 and 81 extending, respectively, between the secondary and primary 40 of the transformer and between the core of the transformer and the primary thereof. These are low capacity condensers and are designed for bypassing high frequency currents.

Now, in considering the connections for coagulation, it will be noted that the requirements for coagulation current are quite opposite from that of the scalpel or cutting current in that a current of very much greater damping is required in order that the proper coagulation effect be secured and so that the current will be essentially free from cutting action. For this modality the connections are as follows: Current is fed to the primary of the main transformer through the lead 28, through pole No. 2 to coagulation contact 53 43, then through lead 44, through the 375 turns or total winding of the choke coil 19, then to the transformer primary through lead 29. The circuit to the primary of the transformer is completed through lead 72, foot switch 14, coagulation contact 68 of pole No. 1, then through lead 71 of the input.

The passage of current through the total winding of the choke coil has the effect of reducing the voltage on the primary of the main transformer and of also reducing its ability to deliver power to the secondary circuit. In other words, it prolongs its time of recovery so that it cannot follow one current impulse to the secondary quickly with a succeeding one as was the case when there was no primary inductance interposed in the circuit. Under these conditions the transformer draws approximately six amperes primary current when the machine is operating instead of thirteen amperes primary current as was the

case when the transformer was connected for the scalpel current.

The secondary 46 of the transformer when used for coagulation is in connection across the spark gap 10 the same as before, but one side of the gap is now connected through lead 31, pole No. 3, coagulation contact 47, lead 48, through the coagulating condenser 21 which is of .032 micro-farad capacity. This it will be noted is a capacity of more than fifteen times that used for the scalpel oscillating circuit condenser and this greater capacity will necessarily be charged at a much slower rate by the main transformer secondary especially because of the fact that the choke coil in the primary tends to reduce the regulation of the transformer as described above.

From this condenser the circuit passes through a lead 49 to the three turn tap 50 of the resonator inductance coil and from the zero turn tap 34 of the resonator inductance coil the circuit is connected to the other side of the spark gap through lead 35. The output for this condition is taken from the 24 $\frac{3}{4}$ turn tap 51 of the resonator inductance coil from which it passes through lead 52 to the coagulation contact 53 of pole No. 4 through lead 39 to one end of the potentiometer coil. The other end of the potentiometer coil 24 is connected to the zero turn tap of the resonator inductance coil as before through a lead 56.

The output of the machine as controlled through pole No. 5 for coagulation is selected by the switch through coagulation contact 57, lead 58 and the coagulation power control slider 12. Inasmuch as a very large oscillating circuit condenser is used, a much higher damping is secured in the output current. The greater ratio between the primary and secondary resonator inductance coil turns still further reduces the regulation and this is also necessary in order to develop the proper voltage on the output.

Now for the diathermy current, the primary of the main transformer current is supplied through lead 28 to pole No. 2, through diathermy contact 59, lead 60, through 325 turns of the choke coil 19, and thence to the primary of the transformer 45 18 through lead 29. Passing the current through 325 turns of the choke coil reduces the primary current to 6 $\frac{1}{2}$ amperes as compared to 13 amperes on the scalpel and 6 amperes on the coagulation. The circuit to the primary of the transformer is completed through lead 75, diathermy contact 70 of pole No. 1 and lead 71 of the input.

Thus it will be seen that the foot switch 14 is utilized when the scalpel and coagulation circuits are employed, but not when the diathermy circuit is being used. For this purpose, the foot switch has been placed in the lead 72 connected to the scalpel and coagulation contacts of the first pole, namely 68 and 69, whereas for diathermy the circuit is completed directly to the diathermy contact 70.

The secondary output from the transformer is now led to the spark gap as in the previous two cases but from one side of the spark gap the circuit is delivered through lead 31 to pole No. 3, thence through diathermy contact 61, lead 62 and through the diathermy condenser 20 which is of .0075 micro-farad capacity and thence to the third turn 50 of the resonator inductance through a 70 lead 63 as was the case in the coagulation circuit.

The capacity of the diathermy condenser is in between the scalpel condenser and the coagulation condenser and provides a current which is of a damping somewhere in between the coagu-

lation and the scalpel circuits. The zero turn 34 of the resonator inductance is again connected to the other side of the spark gap through lead 35. The output of the resonator inductance is connected to the 15 $\frac{1}{4}$ turn tap 64 and extends to the diathermy contact 65 through a lead 66 to the pole No. 4 and thence through lead 39 to the potentiometer. It will be noted that the 15 $\frac{1}{4}$ turn tap is the same tap that is used for 10 the input of the scalpel circuit but this is of no particular significance and need not necessarily occur.

The output of the resonator inductance on diathermy is connected from the slider 13 to the lead 60 to the diathermy contact 67 through pole No. 5 and thence to the electrodes through lead 42.

The correctness of the function of all of the above factors is determined by the exact electrical characteristics of all of the parts used. In order to obtain a satisfactory output on all of the three modalities of scalpel, coagulation and diathermy, the electrical parts must be so proportioned as to operate not only when the 20 circuit is arranged for that particular modality used, but in order to have the machine reasonably simple, since as many parts are used for the circuits in common as is practical. For example, the exact design of the resonator inductance coil—the number of turns used on both the outer and inner tubes and the exact position of tapping these turns off, is absolutely necessary to get proper operation.

The ease of control with which this machine 35 can be used by the operator depends upon the quick and easy selection of the current desired, the exactness and range of control and the quality of the currents produced.

A pilot light 73 burns at all times except when 40 the switch is in off-position, and to accomplish this the light is placed in a lead 74 extending between pole No. 1 and one end of the choke coil 18 since the choke coil is connected to the other side of the input through any of the contacts of 45 pole No. 2.

Having described our invention, we claim:

1. An electro-surgical apparatus, comprising, a transformer adapted to provide current of appropriate power for performing surgical operations, and a spark gap connected to the secondary of the transformer to provide a high frequency current, a capacity and inductance incorporable in said secondary circuit to provide a cutting current, a capacity and inductance 50 incorporable in said circuit to provide a coagulating current, two power control devices, one functionally operative for controlling the power of the cutting current, the other functionally operative for controlling the power of the coagulating 55 current, and means for switching from one type of current and one power control device to the other type of current and other power control device.

2. An electro-surgical instrument, comprising, 60 a transformer adapted to provide current of appropriate power for performing surgical operations, and a spark gap connected to the secondary of the transformer to provide a high frequency current, capacities and inductances incor- 65 porable in said secondary circuit to provide cutting or coagulating current, two power control handles respectively actuating potentiometer brushes, one functionally operative for controlling the power of the cutting current, the other functionally operative for controlling the power 70

of the coagulating current, and means for switching from one type of current, the power of which is controlled by one of said power control handles, to the other type of current, the power of which is controlled by the other of said power control handles. 75

3. In a surgeon's instrument of the type described, means for generating a high frequency electrical current, and means for modifying the power and damping of said current to provide a cutting current, a coagulating current, and a diathermy current, and a switch adapted to incorporate said modifying means into circuit so that at one position of the switch the instrument delivers a cutting current, at another position of the switch the instrument delivers a coagulating current, and at another position of the switch the instrument delivers a diathermy current, and two power control handles, one adapted to adjust the power of the cutting or the diathermy current, the other adapted to adjust the power of the coagulating current. 15

4. An electro-surgical apparatus, comprising, a transformer adapted to provide current of appropriate power for performing surgical operations, a choke coil inserted in the connections to the primary of the transformer, a spark gap connected with the secondary of the transformer to provide a high frequency current, a capacity and inductance incorporable in said secondary circuit to provide a cutting current, a capacity and inductance incorporable in said circuit to provide a coagulating current, a potentiometer for controlling the power output of the machine for either type of current, and a plurality of selector 25 switches comprising switches operable by a common control element and other switches individually operable, the operation of switches of both the above described characteristics serving for establishing the proper connections for the 30 voltage delivered to the transformer and at the same time controlling the selection of the proper capacity and inductance as well as the power output through the potentiometer. 35

5. An electro-surgical apparatus, comprising, a transformer adapted to provide current of appropriate power for performing surgical operations, a spark gap connected to the secondary of the transformer to provide a high frequency current, a condenser and an inductance coil incorporated in said secondary circuit to provide a cutting current, a condenser having a capacity of more than fifteen times that of the first mentioned condenser and an inductance incorporated in said circuit to provide a coagulating current, a selector switch, and power control devices for controlling the respective types of current, said switch including contacts controlled thereby, whereby the operator can shift between the types of current without changing the settings of the power control devices. 45

6. An electro-surgical apparatus, comprising, a transformer adapted to provide current of appropriate power for performing surgical operations, a voltage control device inserted in the circuit to the primary of the transformer, a spark gap connected with the secondary of the transformer to provide a high frequency current, capacities and inductances incorporable respectively in said secondary circuit to provide a cutting current and coagulating current as desirable, a device for controlling the power output of the machine for either type of current, and a plurality of switches, comprising, switches operable by a common control element and other 50

5 switches individually operable, the operation of the switches of both the above described characteristics serving for coincidentally establishing the circuits for either type of current in the proper ratio of voltage, capacity, inductance and power output.

7. An electro-surgical instrument comprising a transformer adapted to provide current of appropriate power for performing surgical and diathermy operations, a spark gap connected to the secondary of the transformer to provide a high frequency current, capacities and inductances incorporable into said secondary current to provide cutting, coagulating or diathermy current, a potentiometer for controlling the power output of the machine for either type of current, and a plurality of switches, comprising, switches operable by a common control element and other switches individually operable, the operation of 10 the switches of both the above described characteristics serving for establishing the proper connections for the voltage delivered to the transformer and at the same time controlling the 15 selection of the proper capacities and inductances as well as the power output through the potentiometer.

8. In a surgeon's instrument of the type described, means for generating a high frequency electrical current and means for modifying the power and damping of said current to provide a cutting current, a coagulating current and a diathermy current, and a switch adapted to incorporate said modifying means into said circuit so that at one position of the switch the instrument 20 delivers a cutting current, at another position 25

of the switch the instrument delivers a coagulating current, at another position of the switch the instrument delivers a diathermy current, and at a fourth position of the switch the instrument delivers no current, said latter position being disposed for traversal by the switch in passing from the diathermy current position to the coagulating current position.

9. An electro-surgical instrument, comprising, 10 means for generating a high frequency electrical current which includes a transformer adapted to provide current of appropriate power for surgical and therapeutic operation, and a spark gap connected with the secondary of said transformer to provide a high frequency current, and means 15 for modifying the power and damping the current furnished by said spark gap and said transformer to provide a cutting current, a coagulating current and a diathermy current, said means including a switch adapted to incorporate said 20 modifying means into the circuit so that at one position of the switch the instrument delivers a cutting current, at another position of the switch the instrument delivers a coagulating current and at another position of the switch the instrument delivers a diathermy current, and a device 25 for controlling the power output of the machine for cutting or coagulating current, said device controlled by a handle for adjusting the power of the coagulating current and said device controlled by a second handle for adjusting the power 30 of the cutting current.

JOHN G. H. LIEBEL.

EDWIN S. FLARSHEIM.
